OARLOCK

Abram L. Shutter, West Haven, Conn.

Application May 12, 1949, Serial No. 92,817

1 Claim. (Cl. 9—26)

1

The present invention relates to oarlocks and in particular to a self-locking oarlock.

A constant and always vexing problem associated with rowing a boat is that of keeping the oars in the oarlocks and the oarlocks in the boat. Not infrequently a rower, and especially an inexperienced one, will fail to immerse an oar-blade into the water or else plunge the blade too deep into the water, with the result that the shaft of the oar rides up out of the oarlock. As a consequence, the rower is sometimes unseated and the oar lost into the water. Moreover, when transporting the oars and oarlocks to and from the boat, the necessity for handling the oars and oarlocks separately is an inconvenience.

An object of the invention is to provide an improved oarlock which is durable, economical to manufacture, and in conjunction with an oar easy to operate.

A further object of the invention is to provide a superior oarlock characterized by a pair of horns bent in opposite lateral directions so as to lock the oarlock to an oar in a manner to prevent separation of the oar and oarlock during normal conditions of rowing and transportation.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a front elevation of the improved oarlock of this invention;

Fig. 2 is a side elevation of the oarlock of Fig. 1 showing the laterally-offset horns;

Fig. 3 is a top plane view of the oarlock of Fig. 1;

Fig. 4 is a side elevation of the oarlock showing its horns in cooperative engagement with the blade of an oar; and

Fig. 5 is an end elevation partly in section of the oar-blade and oarlock on line 5—5 of Fig. 4.

As shown in the drawings, the improved oarlock of this invention is indicated generally at 10 and comprises a substantially U-shaped yoke-portion 11 and an integral stem 12 projecting substantially vertically from the underside of the yoke-portion substantially symmetrically of its respective horns 13 and 14. The lower end of the stem 12 may be provided with a transverse hole 15 for accommodating a pin or similar instrument for temporarily securing the oarlock in a socket in the gunwale of the boat.

2

The oarlock is adapted to cooperatively engage the oar with which it is to be used so that after being mounted thereon, the oarlock and its respective oar may not be separated during ordinary usage, the removal of the oarlock from the oar being accomplished only by orienting the oarlock in a specific relationship to the blade of the oar. To these ends, the oarlock is characterized by the specific configuration of its horns 13 and 14 wherein each is curved inwardly with respect to the center of its yoke-portion 11 and is formed, as shown especially well in Fig. 2, so as to lean outwardly laterally from opposite sides respectively of a vertical plane coextensive with the longitudinal axis of the stem 12 of the oarlock. Moreover, the horn 14 of the oarlock is slightly longer than its horn 13. These characteristic features of the oarlock permit the oarlock to be assembled on an oar only when oriented in a specific relationship to the blade of the oar. Referring especially to Figs. 4 and 5, the blades of oars are, in general, formed with longitudinal ridges 16—16 on opposite sides thereof which originate at the root 17 of the blade and blend into the relatively-wide outer end portion 18 thereof, each ridge defining the intersection of those flat portions 19 of the blade which slope downwardly and away from each other and serve to blend the shaft 20 of the oar into its blade.

As viewed in Fig. 5, this root-portion 17 of the oar will be seen to be substantially diamond-shaped in cross section, the upper and lower apices 16 of which constitute the corresponding ridges of the oar-blade and the lateral apices 21 of which correspond to the feathered edges of the blade. This prismatic root-portion of the blade varies in thickness from a maximum thickness substantially equal to the minimum diameter of the shaft 20 of the oar to a minimum thickness substantially equal to the thickness of the flattened end-portion 18 of the blade. The maximum distance between the outer ends of the horns of the oarlock is less than the maximum thickness of the root-portion of the blade, and consequently, having assembled the oarlock on the oar in the manner hereinafter described, the oarlock will be held from dropping off the oar throughout that portion of its length which is included between its prismatic root-portion 17 and the upper end (not shown) of its shaft, the diameter of which increases gradually from its root-portion to its handle. Moreover, the maximum transverse dimension of the yoke-portion 11 of the oarlock is less than the diameter of the handle-end of the oar and consequently the

oarlock will not slide off this end of the oar during transportation, nor will the oar run out of the oarlock in the event the handle of the oar is released while rowing.

As pointed out above, the respective curved horns of the oarlock are offset laterally with respect to each other so that, in effect, each horn constitutes the partial convolution of a spiral turn about the shaft of the oar so that opposite sides of the oar-shaft are engaged by the corresponding laterally-offset horns of the oarlock along spiral-like lines of contact equally spaced from and on opposite sides respectively of the axis of rotation of the stem 12 of the oarlock. In accordance with this construction, the forces exerted against the respective horns of the oarlock during normal rowing operations are force moments having moment arms equal to the lateral offset of each respective horn and hence the movement of the shaft of the oar during normal rowing operations positively rotates the oarlock and, in particular, its stem 12, in the socket of the gunwale. Thus, the wearing away of that portion of the oar-shaft which is in the oarlock is reduced, the rotation of the oarlock being accompanied by greater ease in rowing.

Since the transverse diameter of the yoke-portion 11 of the oarlock is such as to prevent the oarlock from sliding off the handle-end of the oar, and the distance between the ends of the horns of the oarlock is such as to prevent any portion of the shaft of the oar from riding up out of the oarlocks; the only way in which the oarlock may be separated from the oar is by orienting the horns of the oarlock in the plane of the oar-blade. As pointed out above, the distance between the ends of the horns is less than the minimum diameter of the oar-shaft and the corresponding diameter of the root-portion of the blade and hence the oarlock is not free to be pulled off of the oar when opposite either of these portions thereof. However, by sliding the oarlock down the blade with the base-portion of the yoke 11 of the oarlock engaging against one of the feathered edges 21 of the blade and the free ends of the horns extending over the ridges 16-16, the oarlock will finally arrive at a position wherein cooperation of the feathered edge of the blade with the base of the yoke will have drawn the ends of the oarlock-horns outwardly over the oppositely-disposed ridges 16-16 of the blade at a point thereon at which the thickness of the blade is slightly less than the distance between the ends of the horns, whereupon the oarlock is freed from the blade of the oar. In

the present embodiment, the point of release of the oarlock occurs substantially halfway down the length of the blade. However, the oarlock will not, in general, arrive at its point of release during normal handling of the oar, since the oarlock provides three points of contact with the blade, namely, engagement of the horns with the respective opposite sides of the blade at longitudinally-spaced points therealong; and engagement of the base of the yoke with the feathered edge of the blade. Consequently, when the oar is elevated into a position which might cause the oarlock to slide down off the blade of the oar, the three-point contact of the oarlock with the blade almost inevitably causes the oarlock to bind thereon before reaching its point of release. Thus, while the oarlock may be mounted on and removed from the blade of the oar manually with ease and dispatch, it has been found that the oarlock will not reach its point of release from the blade during normal handling and transportation of the blade and oarlock.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claim are intended to be embraced therein.

I claim:

An oarlock comprising a yoke-portion and a stem projecting substantially perpendicular from the underside of said yoke-portion, said yoke-portion being characterized by a pair of horns, said horns being formed as complementary partially-complete substantially-spiral convolutions.
